UNITED STATES PATENT OFFICE.

THEODORE R. TREIBER AND WILLIAM H. McWHORTER, OF CHICAGO, ILLINOIS.

HANGING STRAP.

Application filed April 4, 1922. Serial No. 549,539.

To all whom it may concern:

Be it known that we, THEODORE R. TREIBER and WILLIAM H. McWHORTER, citizens of the United States, residing at Chicago, in the county of Cook and State of Illinois, have invented new and useful Improvements in Hanging Straps, of which the following is a specification.

This invention relates to straps such as used on street railway cars, and an object of the invention is to provide a strap adjustable as to length to permit it to be extended or collapsed to pre-determined lengths for the convenience of the passengers using the strap, the length of the strap being variable to suit the individual height or arm length of the user.

Another object of this invention is to provide a hanging strap as specified which comprises an advertisement carrying plate adapted to removably receive any suitable type of an advertisement which will be conspicuously displayed while the strap is in use.

A further object of this invention is to provide a strap as specified, which comprises an attaching loop or strap carrying a supporting plate, to which a hand grip strap is adjustably connected, the said connection being arranged to permit the free and easy adjustment of the hand grip strap relative to the carrying plate for adjusting the length of the strap, and also to provide a spring for returning said sections to their collapsed position and to the shortest length of the strap after it has been released.

Other objects of the invention will appear in the following detailed description taken in connection with the accompanying drawings wherein:

40. Fig. 1 is a front elevation of the improved strap.

Fig. 2 is a rear elevation of the improved strap.

Fig. 3 is a longitudinal section through the improved strap.

Fig. 4 is a front elevation of a modified form of the strap.

Fig. 5 is a longitudinal section through the modified form taken on the line 5—5 of Fig. 4.

Fig. 6 is a detail perspective view of a modified form of the advertising plate.

Referring more particularly to the drawings, the improved hanging strap for use in street railway cars or analogous structures

comprises a supporting loop 1 formed of a leather strap or the like which is adapted to be positioned over the carrying rod A, such as carried by street railway cars for the purpose of supporting the straps. The attaching loop 1 extends through a slot 2 in the upper end of the carrying plate 3, the said slot being formed by the punching out of a part of the metal which part is rounded upwardly as shown at 4 to prevent rupturing of the strap. The carrying plate 3 may be constructed of sheet metal or any suitable material and it is provided with a longitudinally extending slot 5 adjacent one edge from which a plurality of downwardly inclining transverse branch slots 7 project. The end portions of the slots 7 are slightly enlarged as shown at 8 to provide depressions for receiving the rivet or pin 9 which is carried by the strap carrying bar 10. The rivet 9 has an enlarged head 11 formed thereon for preventing longitudinal movement of the rivet out of either the longitudinal slot 5 or anyone of the branch slots 7 to prevent disconnection of the bar 10 and carrying plate 3. The strap carrying bar 10 has a hand grip strap 12 carried by its lower end, the said strap being formed in a loop to permit firm gripping thereof by a passenger. A contractile spiral spring 13 is connected to the rivet 9 and to the carrying plate 3, as clearly shown in Figs. 2 and 3 of the drawings, for returning the carrying bar 10 and gripping strap 12 to their uppermost positions after it has been released by a passenger.

In use, when a tall person uses the strap, the rivet 11 is left in the uppermost of the transverse branch slots 7, but when a shorter person uses the strap he may by a slight lateral upward movement on the strap move the rivet into the vertical slot 5, and move it downwardly until the desired elevation of the gripping strap 12 is provided after which the rivet is moved into the adjacent transverse branch slot 7 for providing a rigid support for the gripping strap 12 in its adjusted position. When the gripping strap 12 is released, the spring 13 will contract and owing to the upward incline of the branch slots towards their communication with the longitudinal slot 5 the rivet will be moved out of the branch slot and upwardly along the longitudinal slot 5 to the upper end of the latter.

An advertisement card carrying plate is carried by the bar 10 and is adapted for carrying any suitable type of advertisement.

In Fig. 6 of the drawings a modified form 5 of the advertisement carrying plate is shown which plate, 14' is provided with a relatively large circular opening 15 to receive the head 11 therethrough, and with a transverse guiding slot 16 communicating with the circular opening 15 and with a substantially vertical slot 17 off set from the edges of the slot 16 into which the rivet 9 engages for detachably connecting the modified form of advertisement carrying plate to the strap 15 structure.

In Figs. 4 and 5 of the drawings, a modified form of the improved strap structure is shown, which modified form comprises the carrying plate 20 having the hanging or 20 supporting loop 21 carried by its upper end, and for engagement over the rod A. The plate 20 is connected to the strap 21 by a rivet 23 which rivet is adapted to move into transverse slots 24 similar in construction to the slots 7 and communicating with a longitudinal slot (not shown) in the plate 20. The strap 21 has a gripping loop 25 on its lower end, and it extends throughout substantially the entire length of the 30 carrying plate 20 when the strap structure is in its collapsed position. An advertisement carrying plate 27 which is constructed of sheet metal or analogous material is provided and it has gripping spurs 28 struck therefrom which extend through one portion of the strap 24 as clearly shown in Fig. 5 to securely anchor the plate 27 to the strap structure. A spring 29 is connected to the rivet 23 and to the carrying plate 40 20 for moving the strap structure to its collapsed position. The advertising carrying plates 14, 14' and 27 preferably have channels as indicated at 30 about their side edges and lower ends to provide a support port for a suitable advertisement or placard.

From the foregoing description taken in connection with the accompanying drawings it will be apparent that a strap for street cars has been provided the length 50 of which may be adjusted to suit the convenience of the passenger using the strap.

It is, of course, to be understood that the invention may be constructed in other manners and the parts associated in different 55 relations and, therefore, we do not desire to be limited in any manner except as set forth in the claims hereunto appended.

Having thus described our invention what we claim is:

60 1. In a hanging strap for street cars, a carrying plate provided with a longitudinal slot and a plurality of branch slots communicating therewith, a gripping strap, and means connected to said gripping strap for movement in said longitudinal and branch 65 slots for supporting said gripping strap in adjusted positions relative to said carrying plate.

slots for supporting said gripping strap in adjusted positions relative to said carrying plate.

2. In a hanging strap for street cars or the like, a carrying plate, a supporting strap carried thereby, said carrying plate provided with a longitudinal slot and a plurality of downwardly inclining transverse branch slots, a gripping strap, a pin connected to said gripping strap for movement in said longitudinal slot and into any one of said branch slots for adjusting the position of the gripping strap relative to the carrying plate.

3. In a hanging strap for street cars or the like, a carrying plate, a supporting strap carried thereby, said carrying plate provided with a longitudinal slot and a plurality of downwardly inclining transverse branch slots, a gripping strap, a pin connected to said gripping strap for movement in said longitudinal slot and into any one of said branch slots for adjusting the position of the gripping strap relative to the carrying plate, and an advertisement carrying plate carried by said gripping strap.

4. In a hanging strap for street cars or the like, a carrying plate, a supporting strap carried thereby, said carrying plate provided with a longitudinal slot and a plurality of downwardly inclining transverse branch slots, a gripping strap, a pin connected to said gripping strap for movement in said longitudinal slot and into any one of said branch slots for adjusting the position of the gripping strap relative to the carrying plate, a spring connected to said carrying plate and pin for returning the gripping strap to its uppermost position relative to said carrying plate upon release of the gripping strap by a person.

5. In a hanging strap for street cars or the like, a carrying plate, a supporting strap carried thereby, said carrying plate provided with a longitudinal slot and a plurality of downwardly inclining transverse branch slots, a gripping strap, a pin connected to said gripping strap for movement in said longitudinal slot and into any one of said branch slots for adjusting the position of the gripping strap relative to the carrying plate, a spring connected to said carrying plate and pin for returning the gripping strap to its uppermost position relative to said carrying plate upon release of the gripping strap by a person, and an advertisement carrying plate carried by said gripping strap.

6. In a hanging strap for street cars, a carrying plate provided with a longitudinal slot and a plurality of branch slots communicating therewith, a gripping strap, and means connected to said gripping strap for movement in said longitudinal and branch slots for supporting said gripping strap in 125 adjusted positions relative to said carrying plate.

adjusted positions relative to said carrying plate, and means for returning said gripping strap to its normal position upon release thereof by a person.

- 5 7. In a hanging strap for street cars, a carrying plate provided with a longitudinal slot and a plurality of branch slots communicating therewith, a gripping strap, and means connected to said gripping strap
10 for movement in said longitudinal and branch slots for supporting said gripping

strap in adjusted positions relative to said carrying plate, and means for returning said gripping strap to its normal position upon release thereof by a person, and an advertisement carrying plate carried by said gripping strap. 15

In testimony whereof we affix our signatures.

THEODORE R. TREIBER.
WILLIAM H. McWHORTER.
